UNITED STATES PATENT OFFICE

BENJAMIN J. TRILLER, OF DUBUQUE, IOWA

DOOR-CONCEALED IRONING BOARD

Application filed September 4, 1925. Serial No. 54,462.

This invention has for its primary object the mounting of an ironing board or the like, within a room door so as to be completely contained therein and to permit the door to be used as such as if the ironing board were not so embodied.

With this and other important objects in view as will be set out in the following description and claims, reference will be had to the accompanying drawing forming a part of this specification and wherein like numerals of reference designate corresponding parts throughout the several views, in which:

15 Fig. 1 is a view in elevation of a hung door comprising the invention,

Fig. 2 is a vertical sectional view thereof with the ironing table unfolded to operative position,

20 Fig. 3 is a horizontal sectional view enlarged of a fragment taken on line 3—3 of Figs. 1 and 4,

Fig. 4 is an enlarged vertical sectional view taken on line 4—4 of Fig. 1 and with parts broken away,

Fig. 5 is an enlarged vertical sectional view of a central fragment of the invention with the ironing board in unfolded position, and

30 Fig. 6 is an enlarged detail view in transverse vertical section.

Fig. 7 is a detail horizontal section showing the holding member for the ironing board.

35 In the drawing, reference numeral 2 designates an ordinary door frame, to which is hinged in a usual way a door composed of side stiles 3, top rail 4, bottom rail 5, and front and rear panels. It is immaterial

40 which of the panels is designated the front or rear one, but for purposes of identity, one will be given the reference numeral 6 and referred to as the front panel, and the other which is made up of four sections 7^a—7^b—7^c—7^d will be designated the rear panel.

45 The panel sections 7^a and 7^b are hinged together at their meeting edges and the bottom edge of the panel section 7^b is hinged at 5' to the bottom rail 5. The upper edge 50 of the upper panel section 7^a is provided at

opposite sides with guide pins or trunnions 8 which slide vertically in guide grooves 9 formed in guide strips 10. These strips 10 have secured to them, by gluing or other fastening, the front panel 6 and sections 7^c and 7^d of the rear panel, and form a part of the door structure itself, as if the ironing board combination were not present. The ironing board 15 is provided across its butt end with a cross-bar 16 terminating at its ends in trunnions or guide pins 17 which slide vertically within guide grooves 18 also formed in the said guide strips 10. The ironing board 15 may be moved vertically within its guide grooves 18 free of the panel sections, but may and at times is connected with the panel section 7^a by means of a turn latch, the hooked end 20 of which is insertable through an opening in a plate 22 attached to what will be the under side of the ironing board when in ironing position, and the knob 24 of which is in another position of the board will enter the groove 25 in the same side of the ironing board.

55 In certain positions of the ironing board between the folded and unfolded positions, the same could be canted and displaced from the guide grooves were it not for the provision of means to prevent the same. Such means consists of a U-shaped bail, the side members 30 of which ride in the grooves 18 and are connected together at their lower ends by cross member 31 and at their upper ends are formed into eyes 32 which surround the trunnions or guide pins 17, and it will be obvious that any attempted canting of the board will cause the side members 30 to bind against the guide strips 10 and prevent such canting.

60 The panel 6 is provided on its interior face with a stop block 33 having a beveled outer edge 33' over which the cross member of the said bail rides onto the upper edge 33''. Spaced from this stop block and located within the grooves 18 are stop pieces 34 against which the ironing board trunnions or guide pins 17 engage.

65 The door of this invention is usually the door of a closet adjoining a room, and while the panel 6 may face the interior of the closet 100

with the panel made up of sections 7^a—7^b—7^c—7^d facing the room, it is usual and more desirable to have the panel 6 facing the room and the other panel facing the closet interior, hence the panel 6 is designated herein as the front panel, but may obviously become the normal rear panel. With the panel 6 of the front panel and normally exposed to the room with the closet door closed, it becomes apparent that to unfold the ironing board for use within the room it becomes necessary to open and swing back the closet door to expose the panel sections 7^a—7^b—7^c—7^d to the room, and that after the ironing board is unfolded for use, the door must be held in its open position, for which purpose some efficient means such as the door holder 35 must be employed.

The ironing board when not in use, is folded within the door between its panels, occupying a vertical position and being held therein by turn buttons or similar means 36, the panel sections 7^a and 7^b being held in their vertical positions as in Fig. 1, by means of the hooked end 20 of the latch being engaged behind the plate 22. This latch is rotatable within the panel section 7^a so as to pass freely through the opening 37 in the plate 22 or to engage behind the same.

30 When it is desired to use the ironing board, the latch 20 is turned to a position where it will pass through said opening 37 and the panels 7^a and 7^b will fall or may be moved to the dotted line position of Fig. 2. The fastenings 36 retain the ironing board in vertical position until released, when the board will fall or may be moved to a position to rest upon the panel section 7^a while the latter is still in its said dotted line position. The operator then places his hand beneath the panel section 7^a and forces the same with the ironing board to a horizontal position, as illustrated in Fig. 2 in full lines. What was the outside face of the upper panel section 7^a is now resting against the under face of the ironing board, and the latch knob 24 has passed into the elongated groove 25 in the under face of the ironing board. This groove is only slightly wider than the diameter of the knob 24 so as to prevent lateral displacement of the outer end of the ironing board when in use.

In bringing the ironing board to service position, the anti-canting bail moves upwardly within the groove 18 and its cross member 31 rides up the inclined face 33' of the stop block 33 and snaps over the upper end thereof and assumes a position on the top 33'' thereof as indicated in Fig. 5. Meanwhile the trunnions 17 come into contact with the lower faces of the stop pieces 34. Thus the ironing board in service position is held from movement in one direction by the stop pieces 34 and in another direction by engagement of the cross member 31 with the stop block 33.

65 To fold the ironing board within the door,

its outer end is swung upwardly, previous to which the operator grasps the cross member 31 of the anti-canting bail and during such movement forces it manually over the end of the stop block 33. When against the panel 6, the ironing board is secured by the fastenings 36, and the panel sections 7^a—7^b, which may or may not have moved to the dotted line position of Fig. 2, are moved to closed position by the operator lifting the end of the panel section 7^a having the trunnions 8, causing such trunnions to ascend within the guide grooves 9 until the panel sections 7^a—7^b are in the plane of the panel sections 7^c—7^d, when by properly turning and manipulating the latch, its hooked end 20 will enter the opening 37 in plate 22 and be engaged behind such plate to retain the panels 7^a—7^b in closed or door panel forming position. The door holder 35 is then released and the door used as such in the usual way.

It will be understood that instead of an ironing board, any other suitable board may be substituted, and that such board may form a seat, table or the like. Furthermore, such changes, alterations and modifications may be made in the structure as fall within the spirit of the claims, without limiting the scope of the invention.

What is claimed:

1. In a device of the character described, parallel vertical guides, an ironing board having pintles slideable in said guides, a U-shaped vertical resilient follower slideable in said guides and pivotally connected to the pintles for preventing canting of the ironing board, a detent with an upwardly and outwardly inclined face in the path of said follower, over which the follower rides and another face upon which it rests against downward movement, means for limiting upward movement of the ironing board, and a support for the outer end of the board.

2. In combination, a door including a frame, spaced panels and pairs of vertical guides, one of said panels including upper and lower sections hinged together, one of said sections being hinged to the door frame, guide members on the other hinged section engaging certain of the guides and slideable therein to bring said section to a horizontal position, means for supporting the last mentioned section in horizontal position, an ironing board normally stored between said panels and having pivot pintles engaging the other guides of the door and movable to a horizontal service position, said hinged sections forming a support for the ironing board when the latter is in service position.

In testimony whereof I affix my signature.

BENJAMIN J. TRILLER.
